UNITED STATES PATENT OFFICE

139,343

DESIGN FOR A TOY

Paul E. Temlitz, Chicago, Ill.

Application August 12, 1944, Serial No. 114,857

Term of patent 14 years

(Cl. D34—15)

To all whom it may concern:

Be it known that I, Paul E. Temlitz, a citizen of the United States residing in Chicago, county of Cook and State of Illinois, have invented a new, original, and ornamental Design for a Toy, of which the following is a specification, reference being had to the accompanying drawing, forming a part thereof.

I claim:

The ornamental design for a toy, substantially as shown.

PAUL E. TEMLITZ.
